EDWARD CHESHIRE, OF BERLIN TOWNSHIP, WAUKESHA COUNTY, WISCONSIN

ATTACHMENT FOR COMPOSING-ROOM SAWS

Application filed September 15, 1923. Serial No. 662,841.

This invention relates to an attachment for a composing room saw and more particularly to an extension or long gage for accommodating material which is relatively long or longer than is usually sawed or trimmed, or both, by a composing room saw.

In order to accurately gage lineotype slugs, borders and the like to be cut, the relatively fixed jaw of the composing room saw is provided with a graduated scale, and is also provided with a co-acting side gage arm which extends at right angles to the fixed jaw. Side gages heretofore used were adapted to work within the range of the width of the table or, in other words, the side gage arm is arranged so that it will not move beyond the edge of the table which supports the lineotype slugs and the like. Under such conditions the slugs throughout their full length are supported on top of the table.

In my present invention I provide for gag-
ing and supporting slugs, borders and the like which are so long that they extend be-
yond a side edge of the table and accordingly
are not entirely supported thereby. It is
necessary to support the outer edges of said
slugs and borders when they overhang the
side of the table for otherwise such slugs and
borders might be inaccurately sawed or trim-
med due primarily to a downward shifting
movement of the outer unsupported ends of
said slugs and borders which would cause an
upward movement of said slugs and borders
at the point where they are to be cut.

Accordingly, one object of the invention is
to provide a simple, efficient and durable ex-
tension gage for a composing room saw which
in addition to functioning as a gage will pre-
vent sagging or dropping of the outer ends
of the material to be cut, and, accordingly,
prevent inaccurate cutting.

Another object is to provide an extension
gage for a composing room saw which is
adapted to meet the various requirements under
actual service conditions.

With these and various other objects in
view, the invention may consist of certain
novel features of construction and operation
as will be more fully described and particu-

larly pointed out in the specification, draw-
ings and claims appended hereto.

In the drawings which illustrate an em-
bodiment of the device and wherein like ref-
erence characters are used to designate like
parts—

Figure 1 is a fragmentary top plan view of
a composing room saw equipped with my im-
proved extension gage;

Figure 2 is a fragmentary front elevation
of said gage;

Figures 3 and 4 are sectional views taken,
respectively, in the planes of lines 3—3 and
4—4 of Figure 2; and

Figure 5 is a sectional view taken in the
plane of line 5—5 of Figure 1.

Referring to the figures of the drawings, it
will be noted that the invention is disclosed
in connection with a composing room saw in-
cluding a table 10 with a slot therein for the
reception of the saw 11 which may be driven
from any suitable source through a belt 12.
Ordinarily when the attachment is not in use,
the material to be treated is clamped between
a relatively stationary jaw 13 and a relative-
ly movable jaw 14. The relatively station-
ary jaw 13 is secured to a slide member 15
slidably mounted in a groove 16 in the table
10. The movable jaw 14 is provided with an
elongated shank 17 which is slidably mounted
within a groove 18 within the slide member
15. The relatively stationary jaw member
13 is provided with a graduated scale 19 with-
in the range of the table 10 and normally co-
operates with a side gage arm, not shown.

The extension gage, to which reference will
be had directly, takes the place of the rela-
tively stationary clamping jaw 13 and, among
other things, includes a relatively long bar 20
which is secured to the slide member 15 by
any suitable means such as a machine screw
21. The extension gage is secured to the slide
member 15 in a manner such that it is held
against the clamping jaw 13. It will be un-
derstood that the material to be cut, when the
extension gage is in use, will be clamped be-
tween the main body portion of the extension
gage and the relatively movable jaw 14.

This extension gage has its main body por-
tion extending over a substantial part of the

width of the table and then terminates in a long relatively thin but rigid and sturdy steel bar portion 22. Mounted upon this bar is an adjustable side gage member which includes two main frame portions 23 and 24. The frame member 23 has a groove 25 cut therein to provide a leg 26 which overhangs the bar portion 22 and similarly the frame member 24 has a groove 27 cut therein forming a leg 28 which overhangs said bar portion 22. By means of these overhanging leg portions 26 and 28 the frame members 23 and 24, respectively, may be caused to slide accurately on the bar 22 and be supported thereby. These frame members 23 and 24 are operatively connected to each other by an adjustable screw 29 which is threaded through the frame member 23 and which is journaled in the frame member 24. It is apparent, therefore, that if the screw head 30, which is secured to the screw 29, is rotated the frame members 23 and 24 will be given a relative movement in one direction or the other depending upon the direction of rotation of the head 30.

Normally the frame member 23 is locked to the bar portion 22 by means of a plunger 31 which is received by any one of a plurality of openings 32 in the bar portion 22, and such plunger is yieldably held in such opening by a spring 33 located in a pocket 34 in the member 23 and surrounding the shank 35 of the plunger. The outer end of the shank is provided with a head 36 whereby the plunger 31 may be withdrawn from any one of the openings 32. It will be noted that the gage bar portion 22 is provided with a scale or graduated markings 37 so that by withdrawing the plunger 31 from any opening 32 the side gage members 23 and 24 may be moved along the gage bar for making a general adjustment to accommodate lineotype slugs, borders or the like. After general adjustment is made, a delicate adjustment may be made by rotating the screw head 30. In this connection it will be noted that this head 30 is provided with a graduated scale 38 which cooperates with a zero mark on the frame member 24. Also to facilitate accurate adjustment of the relatively movable side gage member 24, a graduated scale 39 is provided on an arm 40 which is secured to the frame member 23 and extends over the relatively adjustable side gage member 24. In this way the length to which material is to be cut, may be accurately measured or gaged.

As mentioned hereinabove, if the slugs, borders and the like to be cut are unsupported at their outer ends there would be a tendency for them to move, and, as a matter of fact in some instances the inner ends of the slugs to be cut would be caused to shift upwardly, resulting in their being cut on a bias instead of straight. To overcome such inaccurate cutting, there is provided means for support-

ing the outer ends of the material to be cut. This support takes the form of a shelf 41 which is secured to the under side of the relatively adjustable gage frame member 24 by the machine screw 42. To assist in positioning this shelf the latter is provided with a pin 43 which extends into an opening in said frame member 24, and to prevent the machine screw 42 from falling out of the shelf 41, said screw is provided with a collar 44 which is engaged by a small retaining member 45 which is secured to the shelf 41 in any suitable manner.

The main body portion of the side gage bar is provided with a groove 46 for accommodating the overhanging legs 26 and 28 of the frame members 23 and 24, respectively, when the latter are moved to the extreme inner position.

By means of this extension gage relatively long material to be cut may be accurately and quickly measured and supported in a manner to meet all of the requirements for successful commercial use.

Though the present invention has been illustrated in connection with a saw, it will be understood, of course, that the invention is applicable to other cutting means, or to other machines wherein it is desired to accurately position elongated material to be operated upon.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

I claim:

1. In combination, a bed, an elongated positioning member adapted to position material resting upon said bed, a cutting member having a line of cutting action disposed adjacent to one end of said positioning member transversely thereto, an extension gage positioned in parallel relationship with said positioning member on the same side of said line of cutting action as said positioning member, said extension gage including a bar and a stop carried by said bar, and means for adjustably securing said stop at predetermined distances from the line of movement of said cutting member, said stop including relatively movable members and means for moving said members, one of said members having a shelf for supporting material to be operated upon.

2. In combination, a bed, an elongated positioning member adapted to position material resting upon said bed, a cutting member having a line of cutting action disposed adjacent to one end of said positioning member transversely thereto, an extension gage positioned in parallel relationship with said

positioning member on the same side of said line of cutting action as said positioning member, said extension gage including a bar and a stop carried by said bar, said stop including relatively movable members and means for moving said members, one of said members having a shelf for supporting material to be operated upon.

3. In a device of the character described, the combination of a material supporting bed, operating means associated therewith, an elongated gage member disposed adjacent said operating means, said member having a movable support mounted thereon, said support including relatively movable members and stop means for one of the members of said support, and a material holding member on one of said relatively movable members for moving the material with respect to said operating means.

4. In a device of the character described, the combination of a material supporting bed, operating means associated therewith, an elongated supporting member disposed adjacent said operating means and having marking means thereon, said member having a movable support mounted thereon, said movable support including marking means disposed to be related to said first named marking means, said movable support including relatively movable members, one of said members being movable relative to said marking means, and a material supporting member on one of said relatively movable members whereby material can be moved relatively to said operating means.

5. In a device of the character described, the combination of an operating tool, a work support associated therewith, jaw members associated with said work support, a supplementary jaw member secured to one of said first named jaw members and disposed adjacent the other of said jaw members, said supplementary jaw member being provided with a slidable work supporting and moving member, said last named member and said supplementary member having interlocking stop members for setting said slidable member in selected work supporting positions, and means on said slidable member for subsequently moving work supported thereby relatively to said operating tool.

6. In a device of the character described, the combination of an operating tool, a work support associated therewith, jaw members associated with said work support, a supplementary jaw member secured to one of said first named jaw members and disposed in parallel relation to the other of said jaw members, said supplementary jaw member being provided with a slidable work supporting and moving member, said last named member and said supplementary member having interlocking stop members for setting said slidable member in selected work sup-

porting positions, and means on said slidable member for subsequently moving work supported thereby relatively to said operating tool.

7. In a device of the character described, the combination of an operating tool, a work support associated therewith, jaw members associated with said work support, an elongated jaw member secured to one of said first named jaw members and disposed adjacent the other of said jaw members, said elongated jaw member being provided with a slidable work supporting and moving member, said last named member and said elongated member having interlocking stop members for setting said slidable member in selected work supporting positions, said slidable member including relatively movable parts, one of said parts having a track member slidably engaging said elongated member, the other of said parts having means for supporting work, and means cooperating with said parts for selectively moving said parts relatively to each other.

Signed at Milwaukee, Wisconsin, this 12th day of September, 1923.

EDWARD CHESHIRE.
